DOOR CONSTRUCTION

Edward E. Beason, Kansas City, Mo., assignor, by
direct and mesne assignments, to Jacob H.
Peters, Independence, Mo.

Application July 24, 1935, Serial No. 32,842

14 Claims.

(Cl. 20—19)

My invention relates to improvements in door constructions. It is particularly well adapted for use in garage door constructions, and is of the general type in which the door is swung from a vertical closed position to an open substantially horizontal position overhead.

One of the objects of my invention is to provide novel means for pivotally mounting the door so that it may be easily and quickly raised or lowered, which improved means adapts itself to doors of different widths and heights, and which holds the door securely in the open position and prevents its accidental opening.

The novel features of my invention are hereinafter fully described and claimed.

In the accompanying drawing, which illustrates the preferred embodiment of my invention:

Fig. 1 is a vertical section on the line 1—1 of Fig. 3 showing the door in closed position in solid lines, and in open position in dotted lines.

Fig. 2 is a section looking downward on the plane of the line A—B of Figure 1, showing one of the swinging arms and its connections.

Fig. 3 is an inside elevation, partly broken away, showing the door closed.

Fig. 4 is a section on the plane of the line A—B showing the other swinging supporting arm and its connections.

Fig. 5 is an enlarged section on the line 5—5 of Fig. 1, showing one of the supporting guiding rollers and parts connected therewith, and

Fig. 6 is an enlarged view showing in inside elevation one of the guiding rollers and a portion of the door, the guiding channel being shown in cross section.

Similar characters of reference designate similar parts in the different views.

1 designates opposite walls of the garage, 2 the doorway thereof adapted to be closed by the usual garage door 3, which is provided with means by which it can be swung from the closed vertical position, shown in solid lines in Figs. 1 and 3, to the open overhead position, shown in dotted lines in Fig. 1.

For pivotally supporting the door 3 so that it may be swung to and from the open position, there are provided two supporting means comprising two arms, which, preferably, are adjustable as to length. The arms are pivoted to swing on the same horizontal transverse axis on a support, which, as shown, consists of two vertical posts 4 at the inner side of the door 3 and at opposite sides respectively of the doorway 2.

The swinging arms are alike in structure and

mode of operation, excepting that they are related as right and left.

Each swinging supporting arm is provided with an inner tubular member 5 having a horizontal axial portion 6 which is pivoted in a bearing 7 fastened to the front or outer side of the adjacent post 4. Each arm is provided with another member 8 which is longitudinally adjustable with respect to the member 5 and which, as shown, consists of a bar adjustable longitudinally in the tubular end portion of the member 5, to which it can be releasably locked by means of a transverse pin 9, adapted to be disposed in a hole in the member 8 and in any one of a longitudinal row of holes 10 extending through the member 5 transversely. The pin 9 at one end is threaded and has on it a nut 11. Its other end is provided with an eye 12.

The end of the member 5 which is pivoted in the bearing 7, viz., the axial portion 6, is threaded and has fitted on it a nut 13 to hold the member from sliding out of the bearing.

The outer ends of the members 8 are respectively provided with horizontal transverse aligned extensions 14 which extend toward each other and are respectively pivoted in bearings 15 fastened to the inner side of the door 3. The axis of the extensions 14 is parallel with the axis of the axial portions 6 of the members 5, and, preferably, said axes are in substantially the same horizontal plane, whereby the door 3 will be firmly braced against outside pressure applied to its middle portion, said bearings 15 being preferably disposed adjacent to the middle of the height of the door. This disposition of the axis of the swinging supporting arms, also enables the arms to have a minimum of length and weight with a maximum of strength.

For enabling the swinging door supporting arms 5—8 to swing as one unit to prevent cramping or binding of the door 3 when it is swung to or from the open position, connecting means are provided between the extensions 14. In the form of invention shown, such connecting means comprises a transverse horizontal tube 16, which may be in the form of a section of pipe Fig. 3, disposed between the bearings 15 and into the ends of which respectively extend the extensions 14.

To lock the extensions 14 to the tube 16, and to enable the extensions being adjusted toward and from each other, to adapt them to different widths of doors to which they may be applied, the end portions of the tube 16 are respectively provided with longitudinal rows of holes 17. Two pins 18 are respectively removably inserted

through holes provided therefor in the extensions 14. Each pin 18 is adapted to be removably extended through any one of the holes 17 of the adjacent row. As shown in Fig. 3, the transverse 5 horizontal portions 14 of the swinging door supporting arms are of substantial length, thus enabling their lengthwise adjustment in the bearings 15 for substantial distances, to accommodate instances where the supports comprising the 10 posts 4 may be required to be set a distance apart considerably greater than the width of the door-way 2.

For partially counterbalancing the weight of the door 3, two coil springs 19 have one set of 15 ends respectively attached to two clamps 20 respectively fastened to the outer end portions of the members 5.

The other ends of the coil springs 19 are respectively attached to two bolts 21 longitudinally 20 adjustable respectively in two brackets 22 respectively fastened to the posts 4. The bolts 21 have respectively mounted on them two adjustable nuts 23 which respectively bear against the upper sides of the brackets 22. The brackets 22 are 25 disposed higher than and to the rear of the axis of the members 5, whereby the springs 19 will, when the door 3 is closed, exert a tension tending to swing the members 5 and with them the door 3 upwardly and inwardly toward the open 30 position.

As shown in Figs. 1 and 4, each clamp 20 embraces and grips a cylindrical portion of the member 5 of the swinging supporting arm, and as it is a clamp, it can be adjusted lengthwise of and 35 to any desired position on said cylindrical portion, for adapting the spring 19, attached to the clamp, to the weight of the particular door to be partially counterbalanced.

For inwardly guiding the upper end of the door 40 3, when it is swung upwardly on its swinging supporting arms, so that in the fully open position it will be in a substantially horizontal overhead position, as shown in dotted lines in Fig. 1, there are mounted on the door 3 respectively adjacent 45 to its upper corners and upon its inner side, two bearings 24 in which are respectively longitudinally adjustably mounted two horizontal aligned rods 25, which are respectively held in the positions to which they may be adjusted by two set 50 screws 26 fitted in threaded holes in the bearings 24.

Rotatably mounted on the rods 25 at the outer ends thereof are two rollers 27 disposed in two channel bars 28, which serve as guides for the 55 rollers 27 adapted for travel therein. The channel bars 28 are parallel with each other at opposite sides respectively of the doorway 2, with their open channel sides facing toward the door 3. The channel bars extend rearwardly and, preferably, incline slightly downwardly from the doorway 2. They are fastened to the inner sides of the posts 4 and to two posts 29 disposed vertically at opposite edges of the doorway 2 at the inner side thereof.

60 For lifting the door to swing it from the vertical closed position to the open overhead position, it has fastened to its inner and outer sides the two handles 30 and 31.

When the door 3 is lifted from the closed 70 position, the arms 5-8 will swing upwardly with the door, the upper end of which will be guided by the rollers 27 in the channel guides 28 so as to move inwardly, thereby swinging the door on its axis on the extensions 14. The slight downward and inward inclination of the channel

guides 28 will assist in the ease of swinging the door to the overhead position, and it will also prevent any tendency of the door to accidentally swing downwardly to the closed position. However, with the springs 19 given a suitable tension, 5 the channel bars 28 may be disposed horizontally or even be inclined slightly upward.

To assist in swinging the upper end of the door inwardly when the door is being opened, I provide two coil springs 32 which have their lower or 10 inner ends attached to the eyes 12 of the locking pins 9, the other ends of the springs being respectively attached to two screw eyes 33 mounted on the door 3 at the inner side thereof. The tension of the springs 32 is such as to normally 15 tend, but of itself to be insufficient, to pull the door 3 inwardly at its upper end.

Where the space is quite restricted, and where it is desired to dispose the axis of the arms 5-8 at substantially the height shown, while still 20 keeping the springs 19 of considerable length, the members 5 may have crank portions 34 extended downwardly from the axial portions 6 at the inner sides of the bearings 7, as best shown in Fig. 1.

25 In the operation of the door to swing it from the closed to the open overhead position, a person on the inside can grasp the handle 30, or a person at the outer side can grasp the handle 31 to lift the door. The springs 19 and the springs 32 aid 30 in raising the door and swinging it to the open position.

To close the door, the operator grasps the handle 30 and pulls forwardly and downwardly upon it, and this force, assisted by the gravity of 35 the door after it has been started downwardly, results in descent of the door to the vertical closed position.

By adjusting the nuts 23 on the bolts 21 the tension of the springs 19 may be adjusted to 40 properly correspond with the weight of the door.

The lengths of the arms 5-8 may be adjusted, as has been described, to suit the height of the door and the height at which it is desired that the axis of the arms shall be.

Many modifications of my invention, within the scope of the appended claims, may be made without departing from the spirit of my invention.

What I claim is:

1. In a door construction, the combination with 50 a door, a support at the inner side thereof, and supporting means pivoted on parallel horizontal transverse axes to said door and to said support, whereby said door may be swung inwardly at its upper end from a vertical closed position to an 55 open position above said supporting means, of a guide at the inner side of said door which inclines from its outer end inwardly and downwardly in a plane at right angles to said axes, and means on said door having traveling engagement with 60 said guide and disposed above the axis of said door.

2. In a door construction, the combination with 65 a door, and a support at the inner side thereof, of a swinging supporting arm pivoted to said door and to said support on parallel horizontal transverse axes, and a spring attached to said arm and to said door above the axis of said door on said arm and normally exerting a tension tending, but of itself insufficient, to swing inwardly the upper end of said door when the latter is closed.

3. In a door construction, the combination with 70 a door, a support at the inner side thereof, a swinging supporting arm pivoted to said support 75

and to said door on parallel horizontal transverse axes, a guide which inclines from its outer end inwardly and downwardly above said axes, and means on said door above the axis of the latter on said arm having traveling engagement with said guide, of a spring attached to said arm and to said door above said axis of said door on said arm and exerting normally a tension tending, but of itself insufficient, to swing inwardly the upper end of said door when said arm is upwardly swung.

4. In a door construction, the combination with a door, and a support at the inner side thereof, of two swinging supporting arms pivoted on the same horizontal transverse axis to said support and respectively provided with aligned extensions parallel with said axis and pivoted to said door, means connecting said extensions by which they may be made to oscillate with each other, and a spring attached to one of said arms and to said door above the arm to which it is attached and normally exerting a tension tending, but of itself insufficient, to swing inwardly the upper end of said door when the latter is in the closed position.

5. In a door construction, the combination with a door, and a support at the inner side thereof, of bearing means on the inner side and substantially at the middle of the height of said door, a swinging supporting arm pivoted on a horizontal transverse axis to said support, and pivoted to said bearing means on an axis parallel with said first named axis approximately in the horizontal plane thereof, whereby said door may be swung inwardly at its upper end and on and with said arm from a closed vertical position to an overhead open approximately horizontal position, and partial counterbalancing means including a clamp movable lengthwise of and embracing and gripping said arm, and a spring attached to said clamp and exerting a pressure tending but of itself insufficient to swing said door from the closed toward the open position.

6. In a garage door construction, the combination of means forming a horizontal frame extending across the inside of the doorway, beyond the vertical sides of the latter, with a right angle rigid arm at each side thereof, the two arms being parallel and rigid with each other through the front or middle portion of the frame, a pivotal support for the end of each arm, a garage door, and means for removably bolting the back of the door to the outer side of said frame, so that the door is movable into an overhead open position, said bolting being adjustable to change the distance between said arms, and thereby the width of said frame, for doors of different widths, or for different distances between one pivotal support and the other.

7. In a garage door construction, the combination of means forming a horizontal frame extending across the inside of the doorway beyond the vertical sides of the latter, with a right angle rigid arm at each side thereof, the two arms being parallel and rigid with each other through the front or middle portion of the frame, a pivotal support for the end of each arm, a garage door, and means for removably bolting the back of the door to the outer side of said frame, so that the door is movable into an overhead open position, said frame comprising middle and end sections, with the end sections adjustable endwise on the middle section, to vary the distance between said arms.

8. In mechanism for pivotally supporting a door for swinging movement upwardly into an

overhead open position and downwardly into a vertical closed position relatively to a doorway, the combination of two door supporting members adapted to be disposed adjacent to the sides of the door and bent into L-shaped configuration to form two axially aligned arms extending toward each other parallel to the back surface of the door and to also form two rearwardly extending arms projecting inwardly from the door, means for pivotally mounting said rearwardly extending arms on a stationary pivot axis disposed a substantial distance inwardly from said doorway, means for pivotally supporting the door on said axially aligned arms comprising bearing members for attachment to the rear surface of the door and engaging over said axially aligned arms for rotation thereon, means coacting with said axially aligned arms and with said bearing members for permitting relative inward and outward adjustment between said aligned arms and said bearing members to enable the lateral spacing between said rearwardly extending arms to be adjusted, counterbalancing springs connected with said rearwardly extending arms, an upper guide track extending inwardly from said doorway, and guide means carried by the upper portion of said door and travelling along said guide track.

9. In mechanism for pivotally supporting a door for swinging movement upwardly into an overhead open position and downwardly into a vertical closed position relatively to a doorway, the combination of two door supporting members adapted to be disposed adjacent to the sides of the door and being of L-shaped configuration to form two axially aligned arms extending toward each other parallel to the back surface of the door and to also form two rearwardly extending arms projecting inwardly from the door, means for pivotally mounting said rearwardly extending arms on a stationary pivot axis disposed a substantial distance inwardly from said doorway, means for pivotally supporting the door on said axially aligned arms comprising bearing members for attachment to the rear surface of the door and engaging over said axially aligned arms for rotation thereon, means coacting with said axially aligned arms and with said bearing members for permitting relative inward and outward adjustment between said aligned arms and said bearing members to enable the lateral spacing between said rearwardly extending arms to be adjusted, counterbalancing means connected to counterbalance a portion of the weight of said door, and guide means coacting with said door for guiding the opening and closing movements thereof.

10. In mechanism for pivotally supporting a door for swinging movement upwardly into an overhead open position and downwardly into a vertical closed position relatively to a doorway, the combination of a section of pipe extending horizontally across the rear side of the door substantially midway of the height of the door, rod members extending into the open ends of said pipe section at each side of the door, means for mounting the door on said pipe section and rod members, said rod members being adjustable inwardly and outwardly in the outer ends of said pipe section to adapt the mechanism to different widths of doors and to different conditions of installation, arms extending rearwardly from said rod members at each side of the door, means for pivotally mounting said arms on a stationary pivot axis disposed a substantial distance in-

wardly from said doorway, counterbalancing springs connected with said rearwardly extending arms to counterbalance a portion of the weight of said door, an upper guide track extending inwardly from said doorway, and guide means carried by the upper portion of said door and travelling along said guide track.

11. In mechanism for pivotally supporting a door for swinging movement upwardly into an overhead open position and downwardly into a vertical closed position relatively to a doorway, the combination of a tube extending horizontally across the rear side of the door substantially midway of the height thereof, rod members extending into the open ends of said tube at each side of the door, means operatively connecting the door with said tube and rod members, said rod members being adjustable inwardly and outwardly in the outer ends of said tube to adapt the mechanism to different conditions of installation, arms extending rearwardly from said rod members at each side of the door, means for pivotally mounting said arms on a stationary pivot axis disposed a substantial distance inwardly from said doorway and counterbalancing springs connected with said rearwardly extending arms to counterbalance a portion of the weight of said door.

12. In a garage door construction, the combination of a frame extending transversely across the doorway beyond the vertical sides of the latter, and comprising a rigid intermediate member and two rigid end members, each having two arms at angles to each other, means rigidly fastening two of said arms of said end members respectively to said intermediate member, means fastening said frame to one side of the door, and means pivotally supporting the other two arms, so that the door is movable into an overhead open position.

13. In a garage door construction, the combination of a frame extending transversely across the doorway beyond the vertical sides of the latter, and comprising a rigid intermediate member

and two angled end members, each of said end members having two arms at angles to each other, means for removably bolting two of the arms of said end members respectively to said intermediate member, said bolting being adjustable to change the distance between said end members, means fastening said frame to one side of the door, and means pivotally supporting the other two arms, so that the door is movable into an overhead open position.

14. In mechanism for pivotally supporting a door for swinging movement upwardly into an overhead open position and downwardly into a vertical closed position relatively to a doorway, the combination of a section of pipe extending horizontally across the rear side of the door substantially midway of the height of the door, rod members extending into the open ends of said pipe section at each side of the door, means operatively connecting the door with said pipe and rod members, said rod members being adjustable inwardly and outwardly in the outer ends of said pipe section to adapt the mechanism to different widths of doors and to different conditions of installation, arms extending rearwardly from said rod members at each side of the door, bearing members for pivotally mounting said arms on a stationary pivot axis which is disposed a substantial distance inwardly from said doorway and which is parallel with and in approximately the same horizontal plane of said pipe section when the door is in closed position, said rearwardly extending arms comprising means enabling the effective lengths of said arms from said pipe section back to said bearing members to be adjusted, counterbalancing springs for counterbalancing a portion of the weight of the door, and adjustable connecting members for connecting said springs with said rearwardly extending arms, said connecting members being adjustable to different positions along said rearwardly extending arms to adjust the action of said springs.

EDWARD E. BEASON.
